[57] ABSTRACT

A combination residential apartments and service areas building designed to provide senior citizens with individual living quarters, and with stores, personal service shops and the like located in a covered service area, together with an uncovered open air patio area accessible to the apartments but segregated from the service areas. The building comprises rows of side abutting apartments, the entrance ends of the apartments of a row facing the entrance ends of apartments of another row across a covered promenade mall which communicates with the service areas, and the exit ends of apartments of a row facing the exit ends of apartments of another row across an open air uncovered patio area closed at opposite ends to make it inaccessible except through the apartment exits. The arrangement of the component parts of the building makes available to residents all the necessities and amenities of living without leaving the building while maintaining individuality and privacy of dwellings and enjoyment of open air relaxation areas secured against unauthorized invasion. Closing of the inner ends of the patio areas by walls that are parts of the service area enclosure or parts of service area structures results in economical building costs.

COMBINATION MULTIPLE RESIDENTIAL APARTMENTS AND SERVICE AREAS BUILDING

This invention relates to a combination multiple residential apartments and service areas building designed to make available to residents, particularly senior citizens, all the necessities and amenities of protected living under one roof while maintaining individuality and privacy of the dwellings, and enjoyment of open air relaxation areas secured against unauthorized invasion.

The building comprises rows of side abutting apartments, the entrance ends of the apartments of a row facing the entrance ends of apartments of an opposite row across a covered promenade mall which communicates with service areas in the building, and the exit ends of apartments of a row facing the exit ends of apartments of another row across an open air uncovered patio area closed at opposite ends to make it inaccessible except through the apartment exits.

Closing of the inner ends of the open air patio areas by walls that are parts of the service area enclosure or parts of service area shops or other facilities results in economical building costs as well as space saving.

The apartments are covered by roofs that slope toward the uncovered open air patio areas. The covered malls are covered by gable type roofs that slope in opposite directions toward and overhang said apartment roofs whereby drainage of the entire structure is toward said open air patio areas.

The service areas may house a barber shop, beauty shop, snack bar, coin laundry, branch bank, food store, manager's office, and other facilities needed by residents, particularly elderly and infirm persons unable to travel outside of the building. The arrangement provides pleasing, convenient access from private apartments to all necessary services in a protective environment as well as to open air patio areas adjacent the exit ends of the apartments.

In the drawings:

FIG. 1 is a top plan of the ground floor of a building embodying my invention, the roof being omitted.

FIG. 2 is an elevational end view, on an enlarged scale, of part of the end of the building adjacent the building front.

FIG. 3 is an elevational front view, on an enlarged scale, of the central part of the front of the building.

FIG. 4 is a top plan view of the roof of the building shown in FIG. 1.

FIG. 5 is a top plan view, partly in section, of two of the apartments in the first row 11 of apartments, showing the door and window arrangements of all the apartments in the building.

The embodiment of the invention shown in the drawings comprises a building containing six parallel rows of apartments located respectively at the right and left of a main central service area. The number of rows of apartments and the number of apartments in each row may vary. As shown, the rows of apartments extend transversely, that is, parallel to the front and rear walls of the building, and the individual apartments abut each other at their sides. The apartments of two rows that have their entrances facing each other are separated by a covered promenade or mall. The apartments of two rows that have their exits facing each other are separated by a green belt uncovered area which is referred to herein as a patio area, characterized by having closed ends hereinafter described in detail.

As shown in FIG. 1, the building 10 encloses six parallel rows of apartments, the first row 11 being adjacent the front of the building, the next row 12 consisting of apartments that have their entrances facing the entrances of the first row 11; the next row 13 consisting of apartments that have their exits facing the exits of the apartments of second row 12. Said third row 13 has apartments that have entrances facing the entrances of apartments in the fourth row 14. The apartments of the fourth row 14 have exits facing the exits of apartments of the fifth row 15 which have entrances facing the entrances of apartments in the sixth row 16. Thus the entrances of apartments in rows 11 and 12 face each other across a relatively wide covered promenade 17, the entrances of apartments in rows 13 and 14 face each other across a similar covered promenade 18, and the entrances of apartments in rows 15 and 16 face each other across the covered promenade 19. The exits of apartments in rows 12 and 13 face each other across a relatively narrower uncovered green belt area or patio 20; the exits of apartments in rows 14 and 15 face each other across a similar patio 21, and the exits of apartments in rows 11 and 16 each face a narrower uncovered patio area 22, 23, respectively.

The foregoing description of rows 11-16 of apartments, covered promenades 17-19, and uncovered patio areas 20-23, apply to corresponding parts both left and right of the main central service area 25 which extends from the front to the rear of the building 10.

The front walls of the apartments of rows 11, both right and left of the main central service area 25, are sheltered by a wall 26 spaced from the apartment row 11 by the patio area 22. The rear walls of the apartments of rows 16, both right and left of the main central service area 25, are sheltered by the wall 27 of a garage 28 that extends across the rear of the building 10. The wall 27 is spaced from apartment row 16 by the uncovered patio area 23.

The apartments of each of the rows 11-16 are covered by roofs 30 that slope from the entrance sides of the apartment walls toward the uncovered green belt or patio area 22, 20, 21, or 23 which is adjacent the exit side of said apartment row.

Between the roofs 30, in planes higher than said roofs, are gable type roofs 31 that cover the promenade malls 17, 18 and 19, respectively. The roofs 31 slope from the ridge-poles 32 to the eaves 33, the latter being in planes above and spaced from the sloping roofs 30 in overhanging relationship. Drainage from the roofs 31 and 30 is toward gutters 34 mounted adjacent the edges of the roofs 30 above the patio areas 22, 20, 21 and 23.

The main central service area 25 is covered by roof structures similar to the roofs 31. The corresponding parts of the covering for said main central area 25 are designated 31', 32' and 33', said covering being supported by wall 35' provided with window 36'.

An important feature of the building construction of my invention is the arrangement of walls which close one end of the promenade malls 17, 18, 19, and close both ends of the patio areas 22, 20, 21, 23. The inner ends of the covered promenade malls 17, 18, 19 are open and in communication with the main central service area 25. The outer ends of the malls are closed by a wall 35 extending from the ground of floor level upwardly to the roof structures 31 that cover the promenade malls. The walls 35 are provided with an upper

horizontally extending fixed window 36, a fire exit 37, and two vertically extending fixed windows 38 at each side of the exit 37. Each of the green belt or uncovered patio areas 20, 21, has a closed inner end which may be a single vertical wall 40 separating that end from the central service area 25, or it may be part of a service unit 41 that includes a wall 40 and other structural parts utilized as a snack bar, coin laundry, or other service unit. The wall 40, whether a single wall or part of a service unit 41, serves to preserve privacy of the patio areas, and unites two rows of apartments, such as rows 12, 13, or rows 14, 15. The outer end of each patio area 20, 21, is closed by a solid wall 42 provided with an emergency exit 43 and a vertically disposed fixed window 44 at each side of the exit 43.

The central main service area 25 may include a variety of stores, shops, and facilities such as lounge, library, beauty shop, barber shop, laundry, and the like. As shown in FIG. 1, a general store 45 and manager's office 46 are located in the front of the building at opposite sides of the entrance 47. The number of service units 41 may equal the number of open air patio areas such as 20, 21, at each side of the central service area 25, thus providing four walls 40 for closing the inner ends of said patio areas and thereby tying together the apartment exit facing rows 12, 13 and rows 14, 15 and rendering the open air patio areas completely private for residents' use. The covered promenade malls 17, 18, 19 are closed at their outer ends by walls 35 for security, but provide entrance access to the facing apartments of rows 11-12, 13-14, and 15-16.

In FIG. 5 the entrance door of an apartment is designated 50, exit door 51, windows 52 and an entrance designating area 53. The latter may consist of colored cement distinguishable from the rest of the floor of the mall 17, 18 on 19, or other means for identifying the entrance of each apartment.

Entrance and exit openings in the garage 28 have not been shown but may be conventional in arrangement and required number. The space utilized for various service facilities in the central service area 25 may be varied and may include the undesignated central area at the rear of the building.

I claim:

1. A combination multiple residential apartments and service areas building designed for senior residents and providing indoor and outdoor privacy and security, comprising

a. a plurality of straight parallel rows of wall enclosed apartments located in side abutting relationship, each apartment having a front and a rear entrance-exit door, one group of said rows of apartments at the left and another group at the right side of said building, the front ends of said apartments in a row facing the front ends of apartments in an opposite row, and the rear ends of apartments in a row facing the rear ends of apartments in another opposite

- row,
- b. a covered promenade mall between the front ends of apartments of two front facing rows extending the entire length of said rows to the outer side of the building, and providing mall access to each apartment of said two front facing rows,
  - c. an uncovered open air patio area between the rear ends of apartments of two rear facing rows extending the entire length of said rows to the outer side of the building, and providing patio access to each apartment in said two rear facing rows,
  - d. an outer side wall of the building closing the outer end of the covered promenade mall, said side wall being provided with an emergency door openable only from within for exit purposes only,
  - e. an outer side wall of the building closing the outer end of the uncovered open air patio, said side wall being provided with an emergency door openable only from within for exit purposes only,
  - f. a main covered service area between said left and right side groups of rows of apartments, the inner ends of said promenade malls communicating with said service area, and
  - g. service walls closing the inner ends of the said patio areas and segregating said patio areas from said main service area and from said covered malls,

whereby residents are afforded indoor and outdoor privacy and protected against the invasion by unauthorized persons in their apartments and patio areas, while providing emergency exits communicating directly with each apartment from and through a mall and communicating directly with each apartment rear end through a patio area.

2. The building defined by claim 1, in which the covered promenade mall has a longitudinally extending gable type roof which slopes from its transverse center downwardly toward the tops of the apartments of two rows of front end facing apartments, and said apartments of each row have continuous roofs that slope downwardly toward the uncovered patio areas, said mall roof being on higher planes than and overhanging the apartment roofs whereby drainage of the entire roofed areas is distributed evenly to the patio areas from said apartment and mall roofs.

3. The building defined by claim 2, in which the roof of each covered promenade mall is supported by said mall end wall which is upwardly extended and has windows providing light for said promenade mall.

4. The building defined by claim 1, which includes service facilities structures in the main service area, and in which the service walls closing the inner ends of the uncovered open air patio areas each constitute part of a service facility structure in said main service area, whereby the service walls serve the said dual function and save building costs.
